UNITED STATES PATENT OFFICE.

HERBERT H. HENNEGIN, OF ANDERSON, INDIANA, ASSIGNOR TO THE
BUCKEYE MANUFACTURING COMPANY, OF SAME PLACE.

DESIGN FOR A GAS-ENGINE BODY.

SPECIFICATION forming part of Design No. 34,905, dated August 6, 1901.

Application filed July 1, 1901. Serial No. 66,780. Term of patent 14 years.

To all whom it may concern:

Be it known that I, HERBERT H. HENNEGIN, a citizen of the United States of America, residing at Anderson, in the county of Madison and State of Indiana, have invented and produced a new and original Design for Gas-Engine Bodies, of which the following is a specification, reference being had to the accompanying drawings, which form a part hereof.

In the said drawings, Figures 1 and 2 are perspective views of the gas-engine body looking at it from opposite sides.

The design consists of a rectangular oblong body A, provided at each end with a rectangular lateral extension B, these extensions being on the same side of the body. At each end the body is also provided with a transverse horizontal flange C, which is formed at the lower corner of the body and extends entirely across the same and the adjacent side

of the extension B. In each end of the body is formed a circular opening D, and in the side of the body opposite the extensions B is another circular opening E. At each side of the opening E is a rectangular opening F, and on the opposite wall of the body, midway between the projections B, is formed a tubular extension G. In the top wall of the body is formed a rectangular opening H.

What I claim is—

The design for a gas-engine body substantially as described and shown.

In testimony whereof I hereunto affix my signature, in the presence of two witnesses, this 27th day of June, 1901.

HERBERT H. HENNEGIN.
